[57] CLAIM

The ornamental design for a portable card imprinter, substantially as shown.

DESCRIPTION

FIG. 1 is a frontal perspective view of the portable card imprinter, showing my new design;

FIG. 2 is a top plan view thereof;

FIG. 3 is a front elevational view thereof;

FIG. 4 is a side elevational view thereof, as viewed from the right hand side of FIG. 2;

FIG. 5 is a side elevational view thereof, as viewed from the left hand side of FIG. 2;

FIG. 6 is a bottom plan view thereof;

FIG. 7 is a rear elevational view thereof; and

FIG. 8 is a plan view of the portable card imprinter in its fully open position.
